UNITED STATES PATENT OFFICE.

EDWARD KURTH, OF BLOOMFIELD, NEBRASKA.

WHIP-SOCKET LOCK.

1,253,257.

Specification of Letters Patent. Patented Jan. 15, 1918.

Application filed September 11, 1916. Serial No. 119,527.

To all whom it may concern:

Be it known that I, EDWARD KURTH, a citizen of the United States, residing at Bloomfield, in the county of Knox and State 5 of Nebraska, have invented certain new and useful Improvements in Whip-Socket Locks, of which the following is a specification.

The present invention has reference, generally, to improvements in whip sockets, and 10 the invention relates, more particularly, to a whip socket lock.

The invention has for its principal aim and object to provide a whip socket with novel means for releasably holding the whip 15 within a socket, the locking means being controlled by a suitable key so that when the driver of the vehicle desires to leave the vehicle he will be able to operate the locking means to effectively retain the whip within 20 the socket and thereby prevent unauthorized persons from stealing the whip, incidentally saving the driver or owner of the vehicle from loss and inconvenience.

The invention also consists in the provision of a novel sleeve which is to be carried 25 by the whip and coöperate with the locking means so as to increase the efficiency of the device in general.

More particularly, the present invention 30 embraces improved locking lugs adapted to engage ears on the sleeve and the socket so as to consequently anchor or hold the whip within the socket, improved means being also provided for adjusting the locking means.

35 A more specific object of the invention consists in the provision of a novel support for the locking lugs as well as novel means for guiding the lugs when actuating.

Among the other aims and objects of the 40 invention may be recited the provision of a device of the character mentioned with a view to compactness, the number of parts of which are few, the construction simple, the cost of production low, and the efficiency high.

Other improvements and novel details in the construction and arrangement of the various parts of the device will be brought out 45 more in detail in the description to follow, which, for a clear understanding of the invention, should be considered in connection

with the accompanying drawings forming a part thereof and wherein is disclosed for the purpose of illustration, a convenient and satisfactory embodiment of the invention. 55 It is to be noted, in this connection, that minor changes in the construction and arrangement of the parts may be made without departing from the spirit of the invention, or principle of the operation of the various 60 parts.

In the drawings:

Figure 1 is a vertical section of my invention partly in elevation, showing the locking means in an open position. 65

Fig. 2 is a vertical section of my invention showing the locking means in a closed or locked position.

Fig. 3 is a plan view of the whip supporting plate. 70

Similar characters of reference are employed in all of the above described views, to indicate corresponding parts.

Referring now, more particularly, to the drawings I provide a whip socket 1 which 75 may be and preferably is of a cylindrical formation. A main supporting disk 2 is rigidly connected within the socket in spaced relation to the bottom thereof. A whip supporting plate 3 desirably of a circular conformation has spaced parallel arms 4 depending from opposite sides thereof and rigidly connected in any suitable manner to the disk 2 to support the plate 3 in spaced relation with the disk. The plate is also provided at diametrically opposite points on its periphery with recesses 5 while a sleeve 6 has its upper end serrated to provide teeth 7 for engagement with the handle end of the whip 8, slotted ears 9 depending from diametrically opposite points of the sleeve so as to pass through the recesses 5 and allow the whip and sleeve to be supported on the plate 3. 85 90

Now, in order to releasably hold or lock 95 the whip within the socket, I have provided my improved triangular support generally designated by the numeral 10 which has vertically spaced flanges 11 extending in spaced parallel relation from the vertex 100 thereof. Pivotedly supported between the flanges 11 by means of a suitable pin 12 are

the locking lugs 13 the inner ends of each of which terminate in loops 14 to facilitate the pivotal mounting thereof, while the outer ends are pointed as at 15 for a purpose that 5 will presently appear. A guide member generally designated 16 which may be and preferably is of an inverted U-shaped configuration has its intermediate portion rigidly connected to the under surface of the plate 3 by 10 means of a suitable fastening device 17 while the sides or flanges are provided with oppositely disposed diagonally extending openings 18 for supporting the pointed ends 15 and guiding the lugs through the slotted ears 15 9 when the whip is within the socket.

For the purpose of adjusting the locking means to consequently removably hold or anchor the whip within the socket, I have provided my improved adjusting screw 19, 20 the said screw being mounted in a corresponding central opening in the disk 2 and having the outer end reduced as indicated by the numeral 20 and provided with a shoulder upon which rests the intermediate portion 25 of the support 10, the reduced end 20 being rotatably mounted in an opening in the said intermediate portion while a retaining element 21 is rigidly connected to the reduced end subsequent to the arrangement of the 30 intermediate portion of the support 10 thereabout. The opposite end of the screw 19 is reduced and squared as indicated by the numeral 22 and is removably engageable by the recessed end 23 of a suitable 35 key 24 insertable in an opening 25 in the bottom of the socket. Incidentally a spacing ring 26 may be arranged about the screw and supported on the disk to consequently prevent the lugs from falling out 40 of the recesses, although by varying the dimensions I can obviate the employment of this ring.

The operation of this invention may be reviewed as follows:—

45 Assuming that the handle end of the whip carrying the sleeve 6 is inserted in the socket so as to rest on the plate 3 and the ears 9 are arranged in the recesses 5, in order to lock the whip in position it is only necessary to insert the key 24 through the opening 25 and engage the squared end 22 and rotate the key so as to raise the screw 19. Inasmuch as the support 10 is raised with the screw and by reason of the fact that 50 the lugs 13 are supported in the guiding openings 15 when the support is raised the said lugs will be forced through the openings and through the slotted ears 9 which are arranged in alinement therewith and be 55 finally anchored in the inner bore or surface of the socket 1 to consequently prevent an unauthorized person from surreptitiously removing the whip. Of course the key 24 can be removed and kept by the driver.

When releasing the whip it is only necessary to place the key in position to rotate the screw 19 in an opposite direction which will draw the lugs back to their former position.

As many changes could be made in the 70 above construction and many apparently widely different embodiments of this invention could be made without departing from the scope thereof, it is intended that all matter contained in the above description 75 or shown in the accompanying drawings shall be interpreted as illustrative and not in a limiting sense.

Having thus described my invention, what I claim as new and desire to secure by Letters Patent is:

1. A whip socket lock including in combination with a whip, a sleeve carried by the inner end thereof, and ears extending from the inner end of the sleeve, a socket, a supporting disk mounted in the socket, a plate supported in spaced relation on the disk and provided on its outer periphery with oppositely disposed recesses for receiving the ears to allow the whip to rest on the 90 plate, locking means, and means for adjusting the locking means to removably anchor the ears to the socket.

2. A whip socket lock including in combination with a whip, a sleeve carried by the 95 inner end thereof, and ears extending from the inner end of the sleeve, a socket, a supporting disk mounted in the socket, means for supporting the whip within the socket, pivotally mounted locking members in the 100 socket, means for supporting the outer ends of the locking members and for guiding them when actuated, and means for actuating the locking members to force them through the ears and removably anchor 105 them in the socket to retain the whip within the socket.

3. A whip socket lock including in combination with a whip, a sleeve carried by the inner end thereof, and ears extending from 110 the inner end of the sleeve, a socket, a supporting disk mounted on the socket, means for supporting the whip within the socket, a triangular support, locking lugs pivotally mounted in the triangular support, means 115 for supporting the outer ends of the locking lugs and for guiding them during movement, an adjusting screw mounted in the disk and rotatably connected to the triangular support for raising the support when 120 actuated to consequently force the locking lugs through the slotted ears and removably anchor them in the socket to prevent the withdrawal of the whip, and a key removably associated with the screw for actuating 125 the screw.

4. A whip socket lock including, in combination, a member to be secured to a whip

and having slotted ears thereon, a socket, a support within the socket upon which the end of the whip rests, an adjusting screw rotatably mounted within the socket, locking 5 lugs connected to the adjusting screw, means for guiding the locking lugs during movement, and a key removably associated with the adjusting screw for moving the

locking lugs in the slots of said ears, whereby the whip is anchored in the socket. 10

In testimony whereof I affix my signature in presence of two witnesses.

EDWARD KURTH.
